UNITED STATES PATENT OFFICE.

COLE STICKLE, OF INDIANAPOLIS, INDIANA, ASSIGNOR TO OPEN COIL HEATER & PURIFIER COMPANY, OF INDIANAPOLIS, INDIANA, A CORPORATION.

AUXILIARY FLUID-PRESSURE CONTROL.

Application filed July 15, 1921. Serial No. 484,909.

To all whom it may concern:

Be it known that I, COLE STICKLE, a citizen of the United States, and a resident of Indianapolis, county of Marion, and State 5 of Indiana, have invented a certain new and useful Auxiliary Fluid-Pressure Control; and I do hereby declare that the following is a full, clear, and exact description thereof, reference being had to the accompanying 10 drawings, in which like numerals refer to like parts.

This invention relates to an improvement in auxiliary fluid pressure control mechanism in connection with steam boilers adapted for performing a variety of functions. 15 Herein it is shown particularly for controlling the flue damper of a steam boiler, and also a reducing valve, but it is not limited to such use, as it may be employed for controlling other mechanism.

The chief feature of the invention consists in the combination of an adjustable spring with a weighted lever, and acting independently thereof, for resisting the action of a 25 fluid pressure actuated means, such as a diaphragm in a pilot valve or like auxiliary control, either in an independent fluid pressure line, or in a direct steam line for the ultimate control of the damper or other means 30 sought to be controlled, and adapting the mechanism to act at a predetermined maximum fluid pressure.

Heretofore such auxiliary pilot valve control means has been regulated only by a 35 weighted lever, and in actual practice a relatively long lever and heavy weight are required. With this improvement, having an adjustable spring acting independently of said lever, yet cooperating therewith, it is 40 possible to reduce greatly the length of the lever and size of the weight, so that it will not be in the way, or otherwise objectionable, and also adapt the device for variable fluid pressures as the work or situation may 45 require. The spring can be adjusted to furnish the major portion of resistance; while the lever, which is adjustable in action, will furnish the remaining resistance.

The full nature of the invention will be 50 understood from the accompanying drawings and the following description and claims.

In the drawings, Fig. 1 is a central vertical section through the mechanism, parts 55 being shown in elevation, and parts broken

away. Fig. 2 is a side elevation of what is shown in Fig. 1 with parts broken away. Fig. 3 is a central vertical section through a modified form for steam pressure control, parts being broken away. Fig. 4 is a reproduction of a portion of Fig. 3 on a larger scale with the pilot valve closed. Fig. 5 is a section of the diaphragm shown in Fig. 1 in altered position.

In Fig. 1 there is shown a flue 10 of a 65 steam boiler in which there is a damper 11 shown by dotted lines centrally pivoted on a rod 12 so as to regulate said flue. An arm 13 outside of the flue is rigidly secured to the damper rod 12, and it carries a weight 14 70 sufficient to move the damper to closed position. A chain 15 is connected with the weight 14 and passes over pulleys 16 and 17 to an adjustable weight 18 on a piston rod 19 connected with a piston 20 in the cylinder 21. The weight 18 is sufficient to open the damper 11 unless it is counteracted or regulated by fluid pressure in the lower end of the cylinder 21 acting upward on the piston 20. Without fluid pressure in the cylinder 21, the weight 18 would open the damper; but with sufficient fluid pressure to raise the weight 18, the weight 14 would be 75 permitted to close the damper.

The cylinder 21 is supplied with water under pressure which comes from the displacement tank 121. The water in the tank 121 is subjected to pressure by steam coming in through the pipe 122 and an independent auxiliary pipe 27. Said pipes are connected by a valve chamber 25 and controlled by a pilot valve 26. By interposing the displacement tank between the cylinder 21 and the steam line 122—27, the piston 20 is protected from the steam and other advantages 90 result. A leak valve 24 is in the pipe 122. This valve must always be open sufficiently to permit the steam to leak away after the valve 26 is closed, so that the water can rise in the displacement tank and also lower in 95 the cylinder 21 under the weight 18, and thus return to normal position, in which the piston 20 is at the bottom of the cylinder.

In the construction as it is shown in Fig. 1, the pilot valve 26 is open so that fluid under pressure has actuated the piston 20, lifted the weight 18 and permitted the damper to close. The pilot valve 26 has a valve stem 126 that extends down to a plate 27 on the diaphragm stem 28 that extends through 100 105 110

the upper wall of the diaphragm chamber 29 on a diaphragm plate 30 that is secured to a diaphragm 31, which is flexible material clamped between the upper and lower members of the diaphragm chamber. Steam directly from the steam boiler comes through a pipe 32 to the under side of the diaphragm and actuates the diaphragm, and through the intermediate means actuates and opens 10 the pilot valve 26.

The pilot valve stem 126 rides loosely on the plate 27, the stem having a conical end fitting in a conical recess in the plate. Also the stem 28 is conical at its lower end and 15 fits loosely in the conical recess of plate 30. A frame 35 extends upwardly from the diaphragm chamber 29, as seen in Fig. 2, and upon it there is another frame 37 in which a lever 38 is fulcrumed at 39 upon an upwardly extending link, pivoted at 40. The outer end of the lever 38 has holes 41 in it for a weight hook 42 which carries the weights 43. The lever 38 is fulcrumed in a sleeve 45 secured on the valve stem 126, so 25 that the action of the weight 43 through the lever tends to force the valve stem downward. But in this construction, the weights 43 and the length of the lever 38 are such that they are not sufficient to overcome the 30 ordinary steam boiler pressure in the pipe 32. Therefore, an additional but independent means for aiding in this object is provided in the spiral spring 46 which surrounds the valve stem 126 loosely and rests 35 upon the plate 27 at its lower end and carries a plate 47 on its upper end which screws into the upper part of the frame 35 so as to be vertically adjustable for tensioning the spring 46. Therefore, by tightening the 40 spring 46, it will cooperate with the weight 43 and lever 38, but act independently thereof, in holding the diaphragm down until the maximum steam pressure occurs in the steam pipe 32 from the boiler. When excessive 45 steam pressure enters the pipe 32, the diaphragm will rise against the action of the spring 46 and the lever 38 and open the pilot valve 26.

Therefore, a sensitive and compact means 50 is provided in this invention for regulating the generation of steam in the steam boiler, or the steam pressure therein. For, when the steam pressure is relatively low in the boiler, the diaphragm 30 will be down and the pilot valve 26 closed, and the liquid will 55 all be in the displacement tank 121, so that the piston 20 will be down in the lower end of the cylinder 21 and the weights 18 down, and thus lift the weight 14 and open the 60 damper to cause a draft. When the steam pressure in the boiler has reached the desired maximum, it lifts the diaphragm 30 and opens the pilot valve 26 and admits steam from the pipes 27-122 into the displacement 65 tank 121, which forces the water into the

cylinder 21 and lifts the piston 20 and weight 18, and that permits the weight 14 to move the damper towards closing position. Afterward, if the steam pressure becomes sufficiently low, the spring 46 and the lever 38 70 will return the diaphragm, whereby lever 38 will close the pilot valve against the action of the steam pressure on the diaphragm, and thus shut off steam through the pipe 27 to the displacement tank 121. Then the steam 75

in the upper end of the displacement tank will escape through the leak valve 24 and the water will leave the cylinder 21 and enter the tank 121 under the influence of the weight 18, and said weight 18 will open the damper. 80

By adjusting the spring 46 so that it will have a relatively high tension and will control a goodly portion of the steam pressure, the lever 38 can be comparatively reduced in size so as to enable the mechanism to be used in many situations where a longer lever is impossible or difficult of use. Thus, if the high pressure is 200 pounds, the spring 46 can be adjusted to resist substantially 150 pounds and the lever substantially 50 90 pounds. Since the action of the lever is readily adjustable and controls only a relatively slight pressure, the device is conveniently and exactly controlled. With this construction, it is to be noted that it may be 95 very readily adapted to variable pressures according to the work to be done, or condition of operation, by merely adjusting the weight 43 independently of the spring 46.

In the modified form shown in Figs. 3 and 100 4, there is a high pressure pipe 50 from the boiler, and it is provided with a reducing valve 51 in a suitable valve casing 52 that is connected with a low pressure pipe 53, which is extended for any desirable use where low 105 pressure is required. The valve 51 is opened by a spring 55 which is supported on the cross bar of the frame 56 mounted on the valve casing 52 and acts against a disk 57 on the valve stem 58. The valve is closed by 110 steam from the boiler coming through a pipe 60 into the cylinder and acting on the piston 62 secured on the upper end of the valve stem 58. The pipe 60 is connected with a pipe 63 coming from the same boiler, and they are connected by the valve casing 64 which has in it a pilot valve 65. There is a small vent 66 in the pipe 60 that is always open to relieve the pressure in the cylinder 61 when the pilot valve is closed so as to permit the spring 55 to open the valve 51. There is also a downward bend in the steam line 60 to form a water pocket 67 to protect the piston 62 from excessive heat. 115

The pilot valve is constructed as shown 120 in Fig. 4, being tubular and having ports 165 and 265 above and below the seat of the valve, and it is mounted on a valve stem controlled by the same mechanism which has been heretofore described for 125 130

controlling the pilot valve 26, as shown in Fig. 1, and these corresponding parts in the two constructions are given the same numbers. But the diaphragm is actuated 5 by steam coming from the low pressure pipe 53 through a pipe 70 in order that the pilot valve may be controlled by the pressure in the low pressure pipe.

The mode of operation of this modified 10 construction is as follows. When the reducing valve 51 is closed, as shown in Fig. 3, the pilot valve 65 is open and the steam pressure through the lines 63-60 acts on the piston 62 to close the valve 51. When 15 the pressure in the low pressure pipe 53 lowers below the desired limit, it will permit the diaphragm 30 to lower from the upper position it occupies in Fig. 3, and then the lever 38 will close the pilot valve 20 65, as shown in Fig. 4. That will shut off the steam in the line 63-60 and the leak valve 66 will relieve the piston 62, so that the spring 53 will open the reducing valve 51 and allow steam from the high pressure 25 pipe 50 to enter the low pressure pipe 53. As soon as the desired maximum pressure in the low pressure pipe is again attained, the steam passing through the pipe 70 will elevate the diaphragm and open the steam 30 lines 63-60, and thus again close the reducing valve 51.

With the foregoing modified construction, it is noted that the tension of the spring 46 can be readily adjusted to accommodate the 35 mechanism to wide variations of pressure in the low pressure pipe 53, according to the work that has to be performed, or the condition under which the mechanism is working at any time. The foregoing two forms 40 of mechanism in which said invention can be employed illustrates the nature of the invention in said situations, but the invention is not necessarily limited to the particular uses herein specified for the purpose 45 of explaining the same, as there are other well recognized situations where said invention is advantageously used.

The invention claimed is:

1. Mechanism of the kind described including a valve with a valve stem, a diaphragm casing having a chamber therein, a pipe for supplying fluid under pressure to said chamber, a diaphragm in said chamber, a rod extending loosely through the casing 55 into engagement with the diaphragm so as to be actuated thereby, a plate mounted on said rod and against which the valve stem centrally rests, a spiral spring surrounding the valve stem, with one end against said plate, a frame mounted on the diaphragm casing, a spring-tensioning member loosely surrounding the valve stem and engaging said spring and adapted to screw into said frame so that the tension 60 of the spring can be adjusted independently

of the valve stem, and an adjustable weighted lever pivoted in said frame so as to tend to move said valve stem in the same direction as said spring tends to move said plate on said diaphragm, whereby said 70 spring will act on said diaphragm to resist its movement and said weighted lever will act on the valve stem to close the valve and also cooperate with the spring in resisting said movement of the diaphragm. 75

2. Mechanism of the kind described having a vertical cylinder, a piston therein for operating any desired means, a displacement tank located vertically beside said cylinder and with its lower end in communication with the lower end of the cylinder for supplying liquid under pressure thereto for elevating the piston, means for supplying steam or water under pressure to the upper end of said displacement tank for forcing the liquid therefrom into the cylinder, a pilot valve in said steam or air line, a leak valve in the steam or air line between the upper part of said tank and the pilot valve, means actuated by fluid under pressure for opening said pilot valve, an adjustable weighted lever for closing said pilot valve when the fluid pressure is relatively low, an adjustable spring acting independently in said lever but cooperating therewith for resisting the operating movement of said fluid-actuating means, and means for returning the piston to normal position after the pilot valve is closed and forcing the liquid back into the displacement tank. 90 95 100

3. Mechanism of the kind described having a vertical cylinder, a piston therein for operating any desired means, a displacement tank located vertically beside said cylinder and with its lower end in communication with the lower end of the cylinder for supplying liquid under pressure thereto for elevating the piston, means for supplying steam or water under pressure to the upper end of said displacement tank for forcing the liquid therefrom into the cylinder, a pilot valve in said steam or air line, a leak valve in the steam or air line between the upper part of said tank and the pilot valve, a diaphragm for opening said pilot valve, means for supplying fluid under pressure for operating said diaphragm, an adjustable spring for resetting the actuating movement of said diaphragm, an adjustable weighted lever for closing the pilot valve and cooperating with the spring in resetting the actuating movement of the diaphragm, and means for returning the piston to normal position after the pilot valve is closed and forcing the liquid back into the displacement tank. 110 115 120 125

In witness whereof, I have hereunto affixed my signature.

COLE STICKLE.
